UNITED STATES PATENT OFFICE

FRANK TRIER, OF WESTMINSTER, ENGLAND, ASSIGNOR TO A. C. BALDWIN,
OF BOSTON, MASSACHUSETTS.

MACHINE FOR TRUING GRINDSTONES.

SPECIFICATION forming part of Letters Patent No. 293,203, dated February 5, 1884.

Application filed October 18, 1883. (No model.) Patented in England January 20, 1883, No. 341.

To all whom it may concern:

Be it known that I, FRANK TRIER, a subject of the Queen of Great Britain, residing at Westminster, England, have invented certain new and useful Improvements in Machines for Truing Grindstones, (for which I have obtained Letters Patent in England, No. 341 of January 20, 1883,) of which the following is a specification, reference being had therein to the accompanying drawings.

My present invention relates to cutter-carrying bars, and to frames for carrying the same, and their adaptation to turning or dressing the periphery of grindstones and other surfaces.

Figure 1 is an end view of the frame or bed-plate with the cutter-holding devices mounted thereon. Fig. 2 is a side elevation, partly in section. Fig. 3 is a top or plan view. Fig. 4 is also a plan view, showing the application of the cutters in various positions to the stone. Fig. 5 is a top view, showing the arrangement of concentric cutters applied to the stone. Fig. 6 is a side view of the same. Fig. 7 is a top view, showing two cutters arranged on a right and left hand screw, and adapted to be moved toward each other across the face of the stone. Fig. 8 is a sectional view of a cutter-bar in its socket for holding concentric cutters.

Referring to the drawings, A is the bed-plate, provided with slotted wings or extensions A', by means of which the frame A is secured to the trough-frame of the grindstone, or to any other frame in which the stone to be dressed is mounted. Both sides of the frame A are beveled off, as at a, so as to form guide-slides on which the cutter-carrier is free to move back and forth on the frame. One side 40 of the frame is provided with a projecting ledge, B', which protects the screw-shaft from dust and particles of stone, as will more fully appear.

B is the cutter carrier or holder, the lower portion of which is beveled at b to fit on the guides a. The cutter-carrier is moved back and forth on the frame A by means of a screw-shaft, C, located in bearings in the ends of the frame A, said shaft being adapted to work 50 into a nut or screw-threaded aperture in the fork or bracket F, secured to the under side of

the cutter-carrier B, and is protected from dust and grit by means of the overhanging ledge B' of the frame A.

E is a cylindrical sleeve or band surrounding the cutter-carrying bar O, provided with a projection, p, and a slot, O'. The cutter-carrying bar O is adapted to be moved back and forth within the sleeve E for adjustment to the stone to be dressed, and is held to the 60 desired position on the cutter-bar by means of a set-screw, f.

H is a set-screw, which is seated in the cutter-carrying frame B, and impinges against the end of the sleeve E and holds the cutter-bar 65 up to its work and from backward thrust. The projection p on the sleeve E is adapted to rest on the edge g of the hollow trough-like bottom H of the slide B, which lies underneath the sleeve and prevents the sleeve and cutter-carrying bar from turning around when working, and when it is desired to change the angle of the inclination of the cutter, as seen in the right hand of Fig. 4, all that is necessary to be done is to turn the bar over and allow 70 the projection p to rest on the edge g' of the trough H'.

The stone is rotated in the direction indicated by the arrow y, which exerts a downward pressure on the sleeve E, and the tendency is to rotate said sleeve in the same direction in which the cutter is rotated by its impingement against the stone; the stop p, however, coming in contact with the edge g of the trough, prevents the sleeve from turning 75 farther.

It will be understood from Fig. 4, which is a plan view of the machine operating on a stone, that, when working, the invariable tendency is for the cutter-bar O and sleeve to turn 80 around against the stop, and not in the other direction.

B' is the bushing to which the cutter is secured, and is held in said bushing by means of the bolt C'.

It will be noticed that the hole in the bar O, in which the bushing is secured, is at an angle to the axial line of said bar, so that when said bar is partially rotated the cutting angle of the cutter will be changed, as will more fully appear.

By further reference to Fig. 4 the cutter

shown in full in position 1 is dressing across the periphery of the stone in the direction indicated by the arrow x , the cutter and cutter-frame being carried across the frame A by 5 turning the screw C. When the cutter has arrived about half-way across the stone, it is advantageous to allow the cutter to gradually withdraw or recede from the stone. This is done by slackening the set-screw H. The cutter 10 will then run out of cut into the position shown at 2. The cutter and cutter-carrying slide is then run or worked across the stone (out of cut) to the position shown at 3. The bar O is turned over and set into position by the set-screw H, and the stone is finished against a beveled face. To dress a true arris, the cutter is brought into position shown at 4, and caused to move in the direction of the arrow x^2 by means of the set-screw H, the said cutter 15 20 shaving the side of the stone as it proceeds.

In Fig. 7 I have shown two cutter-carriers mounted on a frame and operated by a single screw-shaft, r, which is provided with right and left handed threads, so that when the shaft 25 is turned the cutters will be caused to approach or recede from each other, as indicated by the arrows, and thus a plain level surface can be given to the face of the stone; or by mounting these cutters in holders, as in Figs. 3 30 and 4, the depth of cut can be diminished as it proceeds toward the center, and the face of the stone be thus dressed with a beveled or rounded surface.

The cutter-carriers M N, Fig. 7, can be set 35 at different levels, so that their cuts can overlap each other. In Figs. 5 and 6 I have shown concentric cutters mounted in the carrying and adjusting devices just described, with their relative arrangement to the stone.

40 In Fig. 8 I have shown a sectional view of a mode of mounting concentric cutters; but as this arrangement forms the subject-matter of a separate application, filed November 6, 1883, No. 110,971, no further reference is made to it 45 here.

I do not claim in this application a cutter mounted on a spindle located within a sleeve or bushing, said sleeve being secured in an inclined hole in the cutter-carrying bars, as this is the subject-matter of a claim in an application filed by me October 18, 1883, Serial No. 109,359. Neither do I claim a round bar in which the cutter-spindle is set at an angle and contained wholly within the bar, nor a cutter-holder in which the cutter-spindle is set eccentrically in a tube or cylinder, and having an aperture for receiving the bushing of the cutter, and adapted in its seat to adjust the position of the cutter with relation to the stone, as these features are embraced in an application filed 50 by me November 6, 1883, Serial No. 110,969.

Having thus described my invention, what I claim, and desire to secure by Letters Patent, is—

1. In a stone working or dressing machine, 65 the cylindrical sleeve adapted to be detachably secured to the cutter-carrying bar, provided with a lug, p, and slot o^2 , in combination with the trough H' and slide B, whereby the angle of inclination of the cutter can be 70 changed by the partial rotation of the sleeve, as set forth.

2. In a stone-dressing machine, the cutter-carrying slide B, having a trough, H', in which is located a sleeve, E, for holding the cutter-carrier O, said sleeve being provided with a lug or projection, p, which is adapted to impinge against the edges of the trough, as and 75 for the purpose set forth.

3. The sleeve E, mounted in the slide B, as 80 described, provided with the slotted projection p, in combination with the cutter-carrying bar O and set-screws f and H, as set forth.

In testimony whereof I affix my signature in presence of two witnesses.

FRANK TRIER.
